UNITED STATES PATENT OFFICE

CLAYTON F. BROWER, OF PLEASANT VALLEY TOWNSHIP, SCOTT COUNTY, IOWA

ONION TOPPER

Application filed August 31, 1927. Serial No. 216,605.

My invention relates to improvements in onion toppers.

The objects of my invention are:

1. To provide a simple, easily operated appliance for cutting the tops from onions;
2. To provide a device which will cut the tops from onions and separate the tops from the onions;
3. To provide an onion topping device which will not clog up and which will handle green as well as ripe onions;
4. To provide an onion topper in which the parts are adjustable to meet various differences of size, ripeness, etc.

I attain these objects by the means illustrated in the accompanying drawings, in which,—

Figure 1 is an end elevation of the feed end of my appliance; Fig. 2 is a front elevation, 20 but showing the frame and some of the supports broken away to disclose the construction of the cutter bars and their mounting; Fig. 3 is a detail vertical section on the line 3—3 of Figure 2, but with the frame broken away 25 and omitting the feed spout, 12; Fig. 4 is a detail cross section view on the line 4—4 of Figure 2, but with the supporting frame broken away; Fig. 5 is a top or plan view of the machine omitting the cutter bars; Fig. 6 30 is an enlarged detail of the slotted cross member, 4; Fig. 7 is an enlarged detail of one end of the knife-bar, 18, and its adjustable mounting.

Similar numbers refer to similar parts 35 throughout the several views.

My device comprises a frame composed preferably of angle-irons having legs, 1, 1^a, 2 and 2^a, at each corner thereof, with cross members, 3 and 4, to brace them. Auxiliary 40 frame members, 5 and 6, are mounted upon the cross members, 4, at each end of the machine and form supports for the bearings for the main shaft, 13^a. At one end of the shaft, 13^a, is mounted a large gear, 13, and a crank, 45 15, is secured to the shaft, 13^a, adjacent the gear, 13.

Upon the shaft, 13^a, is also mounted a large roll, 16, which extends substantially the 50 length of the machine. The shaft, 13^a, and roll, 16, are preferably mounted in the frame

at a slight angle so as to slope from the feed to the discharge end of the machine and thereby facilitate the movement of the onions from the feed spout to the discharge spout.

A table, 11, preferably consisting of a flat board, is adjustably mounted upon brackets, 10, secured to the upper end of the front legs, 2 and 2^a, of the machine and extends the full length of the roll, 16, and under one end of the feed spout, 12, and adjacent the inner end of the discharge spout, 20. The table, 11, is adjustably secured upon the bracket, 10, by bolt, 11^a and wing nut, 11^b. The table, 11, is preferably inclined toward the roll, 16.

Upon the cross members, 4, at each side of the machine, are secured angle or flange plates, 7, each of which has its flange resting upon and secured to its adjacent cross member, 4, with bolts, 7^a, or other suitable fastening means. The bolts, 7^a, extend through 70 slots, 4^a, in the cross members, 4, and the slots, 4^a, provide means by which the position of the flange plates may be adjusted toward or away from the roll, 16.

In the vertical portion of the flange plates, 75 elliptical openings, 18^a, are formed, having their longer diameter extending in a vertical direction. Supporting members, 18^c and 18^a, are united to extensions of the knife-bar, 18. The upper supporting members, 18^a, are preferably tapered as shown in Figure 7 and are mounted in tapered openings in eccentrics, 18^b, and secured thereto by set screws as shown in Figure 7. Each lower supporting member, 18^c, is pivotally seated in a corre- 85 sponding opening in the respective flange plates. In order to adjust the knife-bar, 18, so as to bring it closer to or farther from the path of travel of the cutter blades, 17, it is only necessary to loosen the set screws and 90 turn the eccentrics, 18^b, upon the supporting members, 18^c, and when in the desired position, to tighten the set screws. The openings, 18^a, have their horizontal diameter equal to or slightly greater than the diameter 95 of the eccentric, 18^b, so the eccentric may be turned therein and the elliptical shape of the opening, 18^a, permits lateral adjustment without substantially changing the vertical position of the knife-bar, 18.

Supports, 8, are secured to the flange plates, 7, extending upwardly therefrom and having united to them one end of the arms, 9. In the opposite ends of the arms, 9, a shaft, 14^a, is 5 rotatably mounted which carries a small wheel, 17^a, at each end thereof with a plurality of spiral blades, 17, suitably connected thereto. The spiral blades, 17, are connected together at the middle thereof by braces, 21^a.

10 A small gear wheel, 14, is mounted upon the feed end of the shaft, 14^a, so as to mesh with the gear wheel, 13. The small gear wheel, 14, is preferably proportioned to the large gear wheel, 13, so as to cause the shaft, 14^a, to turn at a much higher speed than the shaft, 13^a. When turning rapidly, the rotating cutting blades will have an action similar to that of a lawn mower and on account of the size of the onion tops, it will be necessary in some cases to cause the rotating cutter blades to rotate very rapidly.

15 In the operation of my device, the crank, 15, is turned in a direction to cause the roll, 16, and the cutting appliance, 17, to rotate over 20 toward each other.

25 The onions are then fed to the machine by being placed in the spout, 12, in which they descend by gravity, landing upon the plate or table, 11. The table, 11, may be stationary 30 or may be movable. When stationary, the motion of the roll, 16, will tend to carry the onions along the table from the feed spout to the discharge spout. If desired, the table may be mounted upon shakers or other appliance to cause it to vibrate.

35 In adjusting the machine, the table, 11, is preferably placed with its nearest edge approximately three-quarters of an inch away from the face of the roll, 16, but this distance 40 may be varied to suit the requirements of particular cases. In general, for large onions, the table may be placed farther from the roll, 16, than with small ones. The very small onions are allowed to pass between the edge 45 of the table, 11, and the roll, 16, and will fall through the open spaces between the blades, 17, of the cutter.

50 The onion tops or stalks will be drawn downward by the forward rotary motion of the cutter bars, 17, and will be cut off by a shearing action between the blades, 17, of the cutter and the knife-bar 18.

55 My machine as illustrated in the drawings, is shown mounted upon a stationary frame, but it may be mounted upon the frame of a movable cultivator or harvester. I have shown my device provided with a crank to be operated by hand. It is also obvious that it may be operated by horse or mechanical 60 power of any kind desired. The size, form and proportions of the various parts may be modified very considerably without departing from the spirit of my invention.

65 I claim:

1. An onion topping machine comprising

a frame, a relatively large feed-roll mounted therein, a feed table mounted in the frame sloping downwardly toward the feed-roll, with its lower edge secured approximately at the level of the axis of the feed-roll, a stationary knife-bar mounted in the frame below the center line of the feed-roll, and a cutter rotatably mounted below the feed table adjacent the knife-bar.

2. An onion topping machine comprising 70 a frame, a relatively large feed-roll mounted therein, a feed table mounted in the frame sloping downwardly toward the feed-roll, with its lower edge secured approximately at the level of the axis of the feed-roll, a stationary knife-bar mounted in the frame below the center line of the feed-roll, and a cutter 75 having a plurality of spiral blades rotatably mounted below the feed table adjacent the knife-bar.

80 In testimony whereof he affixes his signature.

CLAYTON F. BROWER.
